UNITED STATES PATENT OFFICE.

OSGOOD MORRILL REDLON, OF BATH, MAINE.

ADJUSTABLE ROOF COLLAR.

1,425,418.

Specification of Letters Patent. Patented Aug. 8, 1922.

Application filed April 6, 1921. Serial No. 458,913.

To all whom it may concern:

Be it known that I, Osgood M. REDLON, a citizen of the United States, and a resident of Bath, in the county of Sagadahoc 5 and State of Maine, have invented a new and Improved Adjustable Roof Collar, of which the following is a full, clear, and exact description.

This invention relates to improvements in 10 adjustable roof collars which permits pivotal adjustment or connection between the roof collar and the sewer pipe so as to insure a proper relative positioning of the collar and the pipe and enable a tight joint 15 to be had so as to prevent the passage of water inside of the collar.

A further object is to provide an adjustable roof collar of the character stated 20 which can be made in any size to suit the pipe employed, which is capable of adjustment relative to the pipe or the pipe relative to the collar, and which can be conveniently positioned on a roof and operate to make a watertight joint.

25 With these and other objects in view the invention consists in certain novel features of construction, and combinations and arrangements of parts as will be more fully hereinafter described and pointed out in the 30 claims.

In the accompanying drawings—

Figure 1 is a view in side elevation illustrating my improved adjustable roof collar.

Figure 2 is a fragmentary view in longitudinal section on the line 2—2 of Figure 1.

Figure 3 is a view in transverse section on the line 3—3 of Figure 2.

1 represents a tapering or truncated conical casing having its lower larger end integral with or fixed to a roof plate 2, the latter having any suitable incline in accordance with the roof on which it is to be placed. Around the upper end of the casing 1 a lead or other calking ring 3 is provided and outside of this calking ring 3 an iron or other hard metal ring 4 is located. The ring 4 is preferably made with depending perforated ears 5 at opposite sides for the reception of rivets 6, which latter project 45 through said perforated ears through the lower portion of the calking ring 3 and through the upper end of the casing 1 operating as hinge pins to permit pivotal adjustment as will more fully hereinafter appear.

50 7 represents a sewer pipe which projects

upwardly through the casing 1 and through the calking ring 3 and fits snugly within the calking ring 3, the respective ends of the calking ring 3 being pressed tightly 60 against the pipe 7 and the casing 1, as clearly shown in the drawings. Initially, however, the calking ring is flared at its ends to permit the assemblage of parts, and after assemblage, the ring is contracted or tapered 65 at its ends so as to form an effective flaring to exclude water around the pipe.

It will be noted that the ring 4 has an internal taper. In other words, this ring is of largest internal diameter at its upper 70 end and reduces in diameter towards its lower end and the calking ring 3 has a corresponding taper, so that when the parts are together and in working position, the calking ring is held against downward movement and an effective tight joint is had between the parts.

The rivets 6 at opposite sides of the rings enable the flue to have a pivotal adjustment relative to the roof collar as it will be noted 80 that the rings 3 and 4 will move with the pipe in initially positioning the parts so as to take the desired angular position or aligned position relative to the casing 1, and after the parts are once adjusted and in 85 place, the calking ring 3 is forced inwardly at its respective ends giving the necessary tight joint.

Various slight changes might be made in the general form and arrangement of the 90 parts described without departing from the invention, and hence I do not limit myself to the precise details set forth, but consider myself at liberty to make such changes and alterations as fairly fall within the spirit 95 and scope of the appended claims.

I claim:

1. A roof collar, comprising a casing, a ring around the casing, a calking ring interposed between the first-mentioned ring 100 and the casing and projecting above and below said ring, and means pivotally connecting the ring and casing.

2. A roof collar, comprising a casing, a ring around the casing, a calking ring interposed between the first-mentioned ring 105 and the casing and projecting above and below said ring, and rivets projected through the first-mentioned ring, the calking ring and the casing and located at opposite sides 110 of said ring affording pivotal connection or adjustment of said parts.

3. A roof collar, comprising a casing, a ring around the casing, a calking ring interposed between the first-mentioned ring and the casing and projecting above and below said ring, depending perforated lugs at opposite sides of said first-mentioned ring, and rivets located in said perforated lugs and projecting through the calking ring and the upper end of the casing.
- 5 4. An adjustable roof collar of the character described, comprising a flared or trun-

cated conical casing, a roof plate at the lower end of said casing, a pipe projecting upwardly through said casing, a calking ring around the pipe and around the upper 15 end of the casing, a hard metal ring around the outside of the calking ring and having an internal taper fitting snugly against the calking ring, and rivets at opposite sides of said rings pivotally connecting them to said 20 casing.

OSGOOD MORRILL REDLON.
